DESIGN FOR A ROADSIDE LUNCHROOM

George Dilts, Davenport, Iowa

Application July 10, 1947, Serial No. 140,179

Term of patent 14 years

(Cl. D13—1)

To all whom it may concern:

Be it known that I, George Dilts, a citizen of the United States, residing at Davenport, in the county of Scott and State of Iowa, have invented a new, original, and ornamental Design for a Roadside Lunchroom, of which the following is a specification, reference being made to the accompanying drawing, forming a part thereof.

In the drawing, the single figure is a perspective view of a roadside lunchroom embodying my new design. The side of the lunchroom opposite the side shown is substantially similar in appearance.

I claim:

The ornamental design for a roadside lunchroom, substantially as shown and described.

GEORGE DILTS.
